(57) **CLAIM**

The ornamental design for a bimetal thermal protection plate for a power receptacle, as shown and described.

DESCRIPTION

FIG. 1 is a top perspective view of a bimetal thermal protection plate for a power receptacle showing our design; FIG. 2 is a bottom perspective view thereof;

FIG. 3 is a side view thereof;

FIG. 4 is another side view thereof;

FIG. 5 is an end view thereof;

FIG. 6 is an opposing end view thereof;

FIG. 7 is a top view thereof

FIG. 8 is a bottom view thereof; and,

FIG. 9 is an environmental view of the bimetal thermal protection plate for a power receptacle.

The broken lines shown herein are included to show portions of the article and environment that form no part of the claimed design.

1 Claim, 5 Drawing Sheets
